ROTARY COMPRESSOR

John E. Wakeman, Dallas, Tex., assignor of one-fourth to George Counts Preston, Dallas, Tex.

Application June 9, 1936, Serial No. 84,338

1 Claim. (Cl. 230—177)

This invention relates to rotary compressors, and has for the primary object the provision of a device of this character employing reciprocating pistons and cylinders therefor, the latter 5 consisting of a unit rotatably mounted with the cylinders arranged substantially tangentially to the axis of rotation and with the closed ends of said cylinders disposed in the direction of rotation, so that the compression will be in the direction of rotation.

With these and other objects in view, this invention consists in certain novel features of construction, combination and arrangement of parts to be hereinafter more fully described and 15 claimed.

For a complete understanding of my invention, reference is to be had to the following description and accompanying drawings, in which

Figure 1 is a vertical sectional view illustrating 20 a compressor constructed in accordance with my invention.

Figure 2 is a transverse sectional view centrally through the cylinder block offset to show the inlet ports and showing the pistons moved fully 25 within the cylinders and completing the compression strokes of the compressor.

Figure 3 is a view similar to Figure 2, but offset to show the exhaust ports and showing the pistons completing their suction strokes.

Figure 4 is a sectional view taken on the line 30 4—4 of Figure 2.

Figure 5 is a fragmentary sectional view taken on line 5—5 of Fig. 3 but with the block rotated to a different position and showing intake and 35 exhaust ports for a cylinder of the compressor.

Referring in detail to the drawings, the numeral 1 indicates a suitable sectional housing joined together, as shown at 2, and the opposite walls of said housing have openings 3 to rotatably receive a hollow shaft 4. The ends of 40 the shaft project outwardly of the housing 1 and one end has connected thereto an air filter 5, while the opposite end is adapted to be connected to a storage tank (not shown). A partition 6 is located in the shaft 4 and divides said shaft into intake and exhaust ends 7 and 8, respectively. The intake end 7 of the shaft has intake ports 9 for connecting the cylinders 10 to said intake end of the shaft. The exhaust 45 end 8 of the shaft has exhaust ports 11 to communicate said exhaust end of the shaft with the cylinders 10.

A cylinder block 12 is journaled on the shaft 4 and is arranged within the housing and has 50 secured to one side thereof a sleeve 13 surround-

ing the shaft 4 and extending exteriorly of the housing and has secured thereto a power wheel 14. The power wheel may be connected to a power source in any suitable way for the purpose of rotating the cylinder block in a clockwise direction.

The cylinders 10 are formed in the cylinder block 12 and are arranged substantially tangentially to the axis of rotation of said cylinder block or, in other words, are arranged angularly to the 10 shaft 4. Reciprocally mounted in the cylinders are pistons 16 and the inner walls of said cylinders have ports 17 adapted to communicate with the intake and exhaust ports during the rotation of the cylinder block. The pistons are 15 shaped to match the irregular walls of the cylinders, that is, the inner walls in which the ports 17 are formed and these ports 17 overlie both the intake ports 9 and exhaust ports 11, and communicate first with the intake and then with 20 the exhaust ports. These ports are arranged in pairs peripherally spaced around shaft 4, each pair being spaced from the next to provide for a dwell between the compression and exhaust strokes of the pistons.

Supported by the housing 1 are cam tracks 18. Shafts 19 extend into said cam tracks and are equipped with rollers 20 which ride on the tracks. Connecting rods 21 are journaled on the shafts 19 and are pivotally connected to the pistons, 30 as shown at 22. The pivots 22 are located laterally of the shafts 19 and in the direction of rotation of the cylinder block and the latter is provided with sockets forming guides 23 for guide elements 24. The guide elements form an integral part of the connecting rods and are arranged in alignment with the shafts 19. The elements 24 have grooves to reduce friction and to permit any fluid in the guides to escape. The cam tracks are shaped to bring about reciprocation of the pistons in the cylinders during the rotation of the cylinder block. The pistons when moving outwardly of the cylinders draw air into said cylinders which is followed by a dwell at the outer ends of the strokes and then in moving inwardly with respect to the cylinders the pistons compress the air in the cylinders for a limited movement of the pistons on the compression stroke and then force the compressed air through the exhaust end 8 during the pistons completing 45 their compression stroke.

In operation, power is delivered to the power wheel 14 which rotates the cylinder block and brings about reciprocation of the pistons in the cylinders. On the suction strokes of the pistons 55

air is drawn into said cylinders from the atmosphere by way of the intake end of the shaft 4, said air first passing through the filter 5. The exhaust ports during the suction strokes of the 5 pistons are closed to said cylinders. At the end of each suction stroke there is a swell prior to the compression stroke provided for by the conformation of the cam tracks and also the peripheral spacing of the pairs of ports. During 10 the initial compression strokes of the pistons, the exhaust and intake ports are closed to said cylinders, bringing about a compressing of the air in the cylinders. The compressing of said air in the cylinders is in the direction of rotation of 15 the cylinder block. Thereby, after the initial movement of the pistons on their compression strokes, the cylinders communicate with the exhaust ports permitting the compressed air to escape by way of the exhaust end 8 of the shaft 20 4. The escape of the compressed air is aided by the pistons completing their compression strokes.

A compressor of this character will efficiently compress air in a storage tank or like device with a minimum consumption of power and also due 25 to the arrangement of the pistons and cylinders, each revolution of the cylinder block will produce a maximum output of air under a high compression.

The centrifugal action of the piston assembly 30 aids in rotating the block on the suction stroke due to the cam tracks being arranged angularly to the axis of rotation of the cylinder block and the pistons of said piston assembly work outwardly to an increasing radius on their suction 35 strokes. The pistons of the piston assembly work inwardly to a decreasing radius relative to the axis of rotation of the cylinder block on their compression strokes. Since the cam tracks are not moved when contacted by the piston assembly 40 bly, they do not absorb the centrifugal force and the reaction is in the general direction of rota-

tion of the cylinder block. The cylinder block acts as a fly wheel for the compressor.

The exhaust ports are arranged in the hollow shaft 4 and in such a way that the cylinders will be closed to the exhaust end 8 of said shaft 5 during part of the compression strokes of the pistons.

Having described the invention, I claim:

A rotary compressor comprising a cylinder block having flat faces arranged at right angles 10 to each other and provided with an axle opening and cylinders opening outwardly through said faces, said cylinders having ports communicating with the axle opening, a hollow shaft extending through the axle opening, a partition in 15 the shaft separating the ends thereof from each other, said shaft having intake and exhaust ports at opposite sides of the partition to move into and out of registration with the ports of the cylinders during the rotation of the cylinder 20 block, a fixed housing receiving the cylinder block for rotation therein and having the ends of the shaft extending through opposite walls thereof, said cylinders being located tangentially 25 of the shaft, a cam track surrounding the block and carried by the housing, rollers engaging the cam track, shafts connecting the rollers in pairs, said block having guides opening through the flat faces thereof and arranged in alignment 30 with the shafts and at right angles to the axle, pistons in the cylinders, connecting rods journaled on the shafts and having offset portions pivoted to the pistons, guide elements formed on the connecting rods and received by the guides, and a sleeve surrounding a portion of the axle 35 and rotatably supported by the housing and having the block secured to one end thereof and having the other end secured to a power take-off medium.

JOHN E. WAKEMAN. 40
